UNITED STATES PATENT OFFICE.

GEORGE GARR HENRY AND SAMUEL FALES, OF NEW YORK, N. Y.

FIREARM.

Application filed April 8, 1927. Serial No. 181,935.

This invention relates to fire arms and particularly to types known as magazine shot guns, in which the recoil of each successive shell discharge automatically causes 5 ejection of the spent shell and its replacement by an unused shell or cartridge.

Shot guns are used extensively by hunters and sportsmen, in single and double barreled types, subject to the disadvantage of 10 frequent reloading, causing waste of time at inopportune or critical moments.

It is therefore an important object of the present invention to provide a shot gun having a single barrel, water jacketed if desired, provided with a magazine for fresh 15 shells and having means for the instant substitution of an unused shell for that previously exploded and ejected.

A further feature resides in the provision 20 of means to maintain continuous firing of the gun so long as the trigger be held in firing position and the supply of shells is maintained.

Another object is to produce a gun composed of few and simple parts, not readily disarranged and capable of being dismounted and reassembled without difficulty.

These and other valuable objects, which 30 will appear hereinafter are accomplished by the novel construction and arrangement of parts described and shown in the accompanying drawings, forming a material part of this disclosure, and in which:

Fig. 1 is a top plan view of an embodiment of the invention.

Fig. 2 is a partial side elevational, partial longitudinal sectional view of the same showing the trigger held in safety position.

Fig. 3 is a plan view of the breech block, the firing block being omitted.

Fig. 4 is a sectional view similar to Fig. 2 showing the firing block in a retracted position, the trigger being released.

Fig. 5 is like view of the same but showing the firing block in a forward position.

Fig. 6 is a transverse sectional view taken on line 6—6 of Fig. 5.

Throughout the several views the numeral 50 10 designates in general a form of combined pistol grip and stock on which is rigidly mounted a frame 11 carrying a barrel 12.

The barrel may be provided with a spaced 55 encircling tube 13 to act as a water jacket

in reducing the temperature as raised by successive discharges, and attached to the jacket is a finger grip 14 for guiding and partially supporting the gun.

Attached to the front of the stock 10 is a 60 guard 15 into which operatively projects a portion of a trigger 16, held when desired in a forward or safety position by a detent 17 slidably engaged to the stock within the 65 confines of the guard and movable into position to prevent movement of the trigger or release it at will.

The forward portion of the guard contains an opening in which is set the upper 70 end of a downwardly extending magazine 18, open at the top and provided with inwardly curved guides 19 at its side edges to present moderate frictional resistance to the uppermost shell in the magazine, the shells 20 being raised by springs, not shown, 75 within the magazine.

The rear wall of the magazine extends into an opening 21 through the frame 11 to permit entrance of the shells, the forward portion of the opening having an oblique 80 flooring 22 leading to the passage through the barrel 12.

Rearward of the opening 21 are two slots 23 and 24 having a wall 25 between them, the trigger 16 being pivoted in the slot 23 on 85 a pin 26, and in the slot 24, pivoted on the same pin, is a curved detent 27 further explained in detail.

An upright plate 28 is removably but firmly held on the extreme rear end of the 90 frame 11 by a pair of opposed spring detents 29, and carried in the upper part of the plate is a rectangular block 30, through which passes the stem 31, of a rear sight 32, a forward sight 33 extending up from the 95 water jacket 13.

Fixed in the block 30 is a rod 34 extending towards the front and having its forward end engaged in an arcuate element 35, the same being complementary to the front 100 end of the breech block and forming a rear closure for the jacket 13.

A hollow breech block 36 is slidably disposed, as at 37, on the upper side of the frame 11 and is provided with front and rear end plates, respectively 38 and 39 enclosing a chamber 40.

These end plates have openings through which the rod 34 freely passes and extending from the arched outer wall of the breech 110

block 36 is an eye 41 slidable on the rod and adapted to take the thrust of a compression spring 42 encircling the rod and abutting the plate 28.

5 A tube 43 is fixed to extend rigidly between the plates 38 and 39 of the breech block in register with the axis of the barrel 12, and movable longitudinally in the tube is a firing pin 44 normally propelled against a shell by a coiled compression spring 45 disposed within the tube.

10 At the rear of the firing pin are formed a pair of opposed flat lugs 46 and 46' guided by slots 48 in the tube, these lugs being arranged vertically and having angular faces inclined inwardly towards the rear and abrupt right angle at their forward edges.

15 The inreaching portion of the trigger 16 is drawn rearwardly by a tension spring 47 and presents an angularly bent arm 16' extending across the wall 25 to make contact with the lug 46'.

20 The detent 27 is held by a spring 48 to cause an inreaching projection 49 to intercept the lug 46 as the firing pin 44 advances until tripped by contact with a tripper 50 on the opposite rear end of the detent 27.

25 At the forward end of the firing pin 44 is a projection 51 adapted to pass through an opening 52 in the plate 38 and cause percusion of the shell 20 in the barrel.

30 Pivoted to the lower edge of the plate 38, which forms a closure for the breech block 36, is a catch 53 movable in a recess 54 in the forward portion of the frame 11, and also in a corresponding recess 55 in the frame at a point immediately rearward of the magazine 18, the catch engaging the edge of the uppermost shell, causing it to 35 advance on the incline 22 into the barrel, as best seen in Fig. 4, at the forward movement of the breech block and at a time when the firing pin is momentarily restrained by the elements 46 and 49.

35 When the shell has been exploded it is retracted by the rearward movement of a spring latch 56 carried by the breech block 36 at its side to extend into a recess 57 and engage the rim of the shell which is ejected by the rising movement of the next succeeding shell outwardly through the space, at 40 that time occurring between the elements 35 and 38, the breech block having receded under the impulse of the explosion, thus taking full benefit of the recoil.

45 In operation, the magazine having been supplied with shells, it is attached to the frame by any of the devices usually employed, the detent 17 being in a raised position to prevent movement of the trigger 16.

50 When the detent is drawn down the trigger is free to operate and the breech block 36 is initially moved by hand rearwardly as far as it will go, compressing the spring 42 as in Fig. 4, the firing pin being held in

retracted position against the spring 45 by 70 engagement of the lug 46' with the trigger element 16'.

Upon drawing the breech block 36 back the catch 53 engages an unexploded shell and ejects an exploded shell simultaneously. 75

The action of the spring 42 thrusts the breech block 36 forwardly but the firing pin 44 is intercepted by the trigger element 16' engaging the lug 46' until the trigger is pulled, whereupon the element 49 engages 80 the lug 46 until the breech block rear plate 39 contacts the element 50, rocking the curved detent 27 upon its support pin 26, and raising the element 49 out of engagement, permitting the firing pin to be thrust forward by action of the spring 45, and it will be understood that so long as the trigger 85 16 is held back these several operations will be automatically repeated, thus causing a rapid succession of shells to be exploded. 90

It is to be noted that after an initial movement has been imparted to the breech block no further manual operations are required except a constant pressure upon the trigger until the supply of shells is exhausted. 95

It should also be noted that no screws are used in the construction and that all parts are of simple and inexpensive character, readily assembled or dismounted and not readily disorganized.

100 Although we have described our improvements with considerable detail and with respect to certain particular forms of our invention, we do not desire to be limited to such details, since many changes and modifications may well be made without departing from the spirit and scope of our invention in its broadest aspect.

Having thus described our invention, what we claim as new and desire to secure by 110 Letters Patent, is:

1. An automatic gun comprising a frame having a barrel attached, a water jacket surrounding the barrel, a front sight on the front of said jacket, an end plate removably engaged at the rear of said frame, and a rear sight fixed in the upper edge of said plate. 115

2. An automatic gun comprising a frame having a barrel attached, a trackway on said frame, a chambered breech block movable reciprocatively on the trackway by the recoil in a rearward direction, a spring to advance said breech block, a guide for said block fixed in said frame, a tube fixed to the ends of the breech block to extend throughout its length, a firing pin operable in said tube, a spring to propel the firing pin forwardly, a magazine directly below said block having an upwardly inclined passage leading to said barrel, and trigger operated means to control said pin. 120

3. An automatic gun comprising a frame having a barrel attached, a trackway on said

frame, a chambered breech block movable reciprocatively on the trackway by the recoil in a rearward direction, a spring to advance said breech block, a tube fixed to the ends of the firing block to extend throughout its length, a breech pin operable in said tube, said pin having upper and lower lugs arranged in a vertical plane to extend through slots in the wall of said tube, a trigger having a part engageable with the lower lug, a curved detent pivoted adjacent said trigger to engage the upper lug, and means for actuating said detent whereby the movement of said firing pin is controlled.

15 4. A repeating gun having a breech mechanism including a longitudinally movable block, a spring propelled firing pin movable in said block, said block being retracted by the recoil, a slotted guide tube in said block 20 for said pin, upper and lower lugs on said pin to extend through the tube slots, a curved detent pivoted to present a part to engage the upper lug and another part to be actuated by said block to release the first 25 named part, and a trigger having a part to engage the lower lug.

5. A repeating gun having a breech mechanism including a fixed barrel, a longitudinally movable breech block carrying a fixed tube, a slideable firing pin in said tube, a driving spring at the rear of said block, a spring to advance said firing pin, automatic means for locking and unlocking the firing pin with reference to said block at each actuation thereof, a trigger and means actuated by said trigger for controlling the action of said firing pin.

6. An automatic gun having a fixed barrel and a reciprocal recoil operated breech block, a firing pin carried by the breech block, a spring for operating the firing pin, two holding lugs on the firing pin, a trigger having a projection engageable with one of said lugs, a detent having a projection engageable with the other of said lugs, an extension carried by the detent positioned in the path of the breech block for tripping the detent for automatic firing and a tube fixed within the breech block for housing 50 the firing pin, said tube being slotted for ac-

commodating the said two lugs on the firing pin.

7. An automatic gun comprising a fixed barrel, a frame having an upwardly extending rear plate, a rod extending from the rear plate forwardly as far as the barrel, a recoil-operated breech block fitted over said rod to reciprocate thereon, a recoil-absorbing spring operatively positioned on said rod between the rear plate and the breech block, a firing pin carried by the breech block, and a trigger for controlling the actuation of the firing pin.

8. An automatic gun comprising a fixed barrel, a frame having an upwardly extending rear plate, a rod extending from the rear plate forwardly as far as the barrel, a recoil-operated breech block fitted over said rod to reciprocate thereon, a recoil-absorbing spring operatively positioned on 70 said rod between the rear plate and the breech block, a firing pin carried by the breech block, and a trigger for controlling the actuation of the firing pin and a tube fixed inside the breech block, for housing 75 the firing pin.

9. An automatic gun comprising a fixed barrel, a frame having an upwardly extending rear plate, a rod extending from the rear plate forwardly as far as the barrel, a recoil-operated breech block fitted over said rod to reciprocate thereon, a recoil-absorbing spring operatively positioned on 80 said rod between the rear plate and the breech block, a firing pin carried by the breech 85 block, two holding lugs on the firing pin, a tube fixed within the breech block for housing the firing pin, said tube being slotted for accommodating said lugs, a trigger having a projection engageable with one of said 90 lugs, a detent having a projection engageable with the other of said lugs, and an extension carried by the detent positioned in the path of the breech block to be operated thereby for releasing the firing pin for 95 automatic firing.

In testimony whereof we have hereunto affixed our signatures.

GEORGE GARR HENRY.
SAMUEL FALES.
